UNITED STATES PATENT OFFICE.

IRA H. SPENCER, OF HARTFORD, CONNECTICUT, ASSIGNOR TO THE ORGAN POWER COMPANY, INCORPORATED, OF HARTFORD, CONNECTICUT, A CORPORATION OF CONNECTICUT.

HYDRAULIC-MOTOR PUMP.

SPECIFICATION forming part of Letters Patent No. 764,156, dated July 5, 1904.

Application filed August 22, 1903. Serial No. 170,391. (No model.)

To all whom it may concern:

Be it known that I, IRA H. SPENCER, a citizen of the United States, residing at Hartford, in the county of Hartford and State of Connecticut, have invented certain new and useful Improvements in Hydraulic-Motor Pumps, of which the following is a specification.

This invention relates to a hydraulic-motor pump which has a primary valve that is actuated by the movement of the motor-piston and a secondary valve surrounding the primary valve, that is actuated by the pressure of the water according to the position of the primary valve for directing the flow of water to the motor-piston.

The object of this invention is to provide a simple, durable, powerful, and compact construction having the primary valve, the secondary valve, and the water ports and passages so arranged with relation to each other that the primary valve has a long movement, whereby the secondary valve, which has a short movement, may have a long time in which to reverse, thus allowing the motor-piston to take a full stroke without danger that it will strike the end of the cylinder and insuring a uniform and smooth action of the parts.

The machine shown as embodying the invention has a pump-cylinder containing a pump-piston, a valve-case containing pump suction and discharge valves, a superimposed motor-cylinder containing a motor-piston that is rigidly connected with the pump-piston, and a head at the upper end of the motor-cylinder provided with the necessary water ports and passages and containing a freely-movable tubular secondary valve in the center of which is a double-piston primary valve that has a rod which is arranged to be engaged with and moved by the motor-piston.

Figure 1 of the accompanying drawings shows a vertical section of this machine. Fig. 2 shows a sectional view of the cylinders and valve-head on a plane at right angles to the plane of Fig. 1. Fig. 3 shows a sectional view, on larger scale, of the valve-head and the primary and secondary valves.

The pump-cylinder 1 is a section of a tube held between the base 2 and the pump-valve case 3, and the motor-cylinder 4 is a section of a tube of the same diameter held between the pump-valve case and the motor-valve head 5. Bolts 6 extend from flanges projecting from the valve-head to threaded sockets in the base for holding these parts together.

The pump-piston 7 in the pump-cylinder is rigidly connected with a motor-piston 8 in the motor-cylinder by a rod 9, that is suitably packed where it passes through the parts of the pump-valve case which form the ends of the pump-cylinder and the motor-cylinder. The suction-valve 10 on one side and the discharge-valve 11 on the other side are arranged in the pump-valve case so that they may be removed at any time by unscrewing the plugs 12, which support the valve-stems.

The motor-cylinder-valve-head has a bonnet 13 at the top and a bonnet 14 at the bottom, that extends into the motor-cylinder.

The inlet 15 opens through one side of the head and is in communication with the annular chamber 16. The outlet 17 opens through the other side of the head and is in communication with two annular chambers 18. Between the inlet-chamber 16 and the outlet-chambers 18 are intermediate annular chambers 19 and 20.

In the head and extending from one bonnet to the other, so as to line the annular inlet, outlet, and intermediate chambers, is a tube 21. Perforations are made through the lining-tube opposite the inlet-chamber, the outlet-chambers, and the intermediate chambers.

The secondary valve, that is movable in the head, has a tubular body 22, with four cup-shaped packings that fit the lining-tube. The upper and lower packings 23 face outwardly, and the two intermediate packings 24 face inwardly. The opening through the body is closed at the ends by caps 25.

Between the two upper packings is an annular space 26, which is in communication with the annular chamber 27, that is connected by a passage 28 with the upper end of the opening in the body. Between the two lower

packings is an annular space 29, which is in communication with an annular chamber 30, that by a passage 31 is connected with the lower end of the opening in the body. The 5 annular space 32 between the intermediate packings is in communication with the opening in the body at the middle.

The annular chamber 20 is connected by a 10 passage 33 with the upper end of the opening in the motor-cylinder, and the annular space 15 19 is connected by a passage 34 with the upper end of a tube 35, which is held between the head and the valve-case and communicates with the lower end of the opening in the motor-cylinder, Fig. 2. Perforations 36 are made 20 through the body from the interior to the exterior between the middle and the upper end, and perforations 37 are made through the body from the interior to the exterior between the middle and the lower end.

Movable in the central opening in the body is the primary valve, which has oppositely-facing cup-packings 38, which are held separated by a sleeve 39 upon a rod 40, that extends 25 through the lower bonnet, and has a head 41 in an opening in the rod that connects the motor-piston and the pump-piston, Fig. 1.

When the secondary valve is in its lowest position, water under pressure enters the annular space 32 between the intermediate packings and passes through the chamber 20 and passage 33 to the upper end of the motor-cylinder and forces the motor-piston downwardly. The water-pressure is exerted equally in opposite directions upon the intermediate packings of the secondary valve and also enters the opening in the center of the body and is exerted equally in opposite directions between the packings of the primary valve. When 30 the secondary valve is in its lowest position, water under pressure, that enters the opening in the center of the body, passes through the upper perforations 36 and holds the secondary valve down. When the motor-piston is going 35 downwardly, the lower part of the motor-cylinder exhausts through the tube 35 and passage 34 to the annular chamber 19, which is in communication with the outlet through the space 26 and chamber 18. At all times the 40 annular spaces 26 and 29 are in communication with the annular outlet-chambers 18, allowing water to exhaust from above and below the packings of the primary valve. As the motor-piston nears the lower limit of its movement it engages the head of the primary-valve rod and draws down the primary valve. When 45 the primary valve has been drawn way down, the upper packing 38 is carried below the upper perforations 36 and the lower packing 38 50 is carried below the lower perforations 37, so that the water in the head above the secondary valve is allowed to escape through the upper perforations 36, passage 28, and space 26 to the outlet, while the water under pressure 55 between the packings of the primary valve

passes through the lower perforations 37 and lifts the secondary valve. When the secondary valve has reached the upward limit of its movement, the space 32 is in communication with the chamber 19—that is, in communication with the lower end of the motor-cylinder—so that pressure will be exerted upwardly on the motor-piston. At this time the water under pressure above the motor-piston escapes through the passage 33 and space 29 to the outlet. The space 32 between the intermediate packings of the secondary valve is always in communication with the inlet-passage, and the spaces 26 and 29 are always in communication with the outlet-chambers 18. 70 When the motor-piston nears the upward limit of its movement, the primary-valve rod is engaged and moved upwardly, so that the space below the secondary valve is opened to the outlet and the space above the secondary valve is opened to the inlet, causing the secondary valve to change and the pressure on the motor-piston to be reversed. 80

The cup-packings of the primary valve are placed a considerable distance apart, so that 90 the primary valve will have a long slow movement each side of the upper and lower perforations 36 and 37, and these perforations of course must be such a distance apart that they open from the interior to the secondary valve. 95 This allows the secondary valve to move slowly and uniformly in changing its position before the motor and pump pistons reach the limits of their movements. A hydraulic-motor pump constructed in this way operates easily 100 and smoothly without pounding. It is sure in action and durable in use, and it does not clog or become choked with sediment.

The invention claimed is—

1. A hydraulic-motor pump consisting of a pump-cylinder containing a pump-piston, a motor-cylinder containing a motor-piston, a valve-head having an inlet communicating with an annular chamber, an outlet communicating with two annular chambers, intermediate chambers between the inlet-chamber and the outlet-chambers, a perforated tube lining the chambers, bonnets attached to the ends of the head, a tubular secondary valve loosely fitting the lining-tube and having two inwardly-facing cup-packings near the center and two outwardly-facing cup-packings near the ends, a middle annular space that is always in communication with the inlet and two outer annular spaces that are always in communication with the outlet, passages connecting the outer annular spaces with the ends of the opening in the valve-body, perforations connecting the opening in the valve-body with the middle annular space, perforations connecting the opening in the valve-body with the chambers in the lining-tube beyond the outer cup-packings, caps closing the ends of the opening in the valve-body, a primary valve movable in the opening and having two cup-packings fac- 110 115 120 125 130

ing each other at considerable distance apart and a rod extending from the primary valve into a position to be engaged with and moved by the motor-piston, substantially as specified.

5 2. A hydraulic-motor pump having a base with an upwardly-extending flange, a pump-cylinder with its lower end resting upon the base within the flange, a pump-valve case with a downwardly-extending flange fitting the upper end of the pump-cylinder and having an upwardly-extending flange, a motor-cylinder with its lower end resting upon the pump-valve case within the flange, a valve-head with a downwardly-extending flange resting upon the top of the motor-cylinder, flanges extending outwardly from the valve-head, bolts extending from the flanges on the valve-head to the base and holding the base, pump-cylinder, valve-case, motor-cylinder and valve-head together, a pump-piston in the pump-cylinder, suction and discharge valves in the valve-case, a motor-piston in the motor-cylinder and connected with the pump-piston, a tubular secondary valve in the valve-head, a piston primary valve movable in the secondary valve, and a rod connecting the primary valve with the motor-piston, substantially as specified.

25 3. A valve-head having an inlet communicating with an annular chamber, an outlet com-

municating with two annular chambers, intermediate chambers between the inlet-chamber and the outlet-chambers, a perforated tube lining the chambers, bonnets attached to the ends of the head, a tubular secondary valve loosely fitting the lining-tube and having two inwardly-facing cup-packings near the center and two outwardly-facing cup-packings near the ends, a middle annular space that is always in communication with the inlet and two outer annular spaces that are always in communication with the outlet, passages connecting the outer annular spaces with the ends of the opening in the valve-body, perforations connecting the opening in the valve-body with the middle annular space, perforations connecting the opening in the valve-body with the chambers in the lining-tube beyond the outer cup-packings, caps closing the ends of the opening in the valve-body, a primary valve movable in the opening and having two cup-packings facing each other at considerable distance apart and a rod extending from the primary valve, substantially as specified.
